(57) **CLAIM**

The ornamental design for a ceiling fan blade iron, as shown and described.

DESCRIPTION

FIG. 1 is a perspective view from below of a ceiling fan blade iron in accordance with my design, illustrating the environment of said blade iron;

FIG. 2 is an enlarged perspective view from below of the ceiling fan blade iron in accordance with my design, illustrating the environment of said blade iron;

FIG. 3 is an enlarged perspective view from below of the ceiling fan blade iron in accordance with my design;

FIG. 4 is an enlarged perspective view from above of the ceiling fan blade iron in accordance with my design;

FIG. 5 is a bottom plan view of the ceiling fan blade iron in accordance with my design;

FIG. 6 is a side elevation view of the ceiling fan blade iron in accordance with my design; the opposite side being a mirror image of that shown

FIG. 7 is a proximal view of the ceiling fan blade iron in accordance with my design; and,

FIG. 8 is a distal view of the ceiling fan blade iron in accordance with my design, illustrating the environment of said blade iron.

The broken lines showing environmental structure are for illustrative purposes and form no part of the claimed design.
